UNITED STATES PATENT OFFICE.

FRANK ALBERT WALTON, OF SPARKS, NEVADA, ASSIGNOR OF ONE-THIRD TO FRED WILLIAM STEINER, OF SPARKS, NEVADA.

AUTOMATIC TRAIN CONTROL.

1,241,454.

Specification of Letters Patent. Patented Sept. 25, 1917.

Application filed October 31, 1916. Serial No. 128,736.

To all whom it may concern:

Be it known that I, FRANK ALBERT WALTON, a citizen of the United States, residing at Sparks, in the county of Washoe and 5 State of Nevada, have invented new and useful Improvements in Automatic Train Controls, of which the following is a specification.

This invention relates to certain novel and 10 useful improvements in automatic train stopping apparatus.

In carrying out the present invention, it is my purpose to provide an automatic train stopping apparatus which will operate to 15 apply the brakes in the event of the train running into a danger zone, and which will embody a valve located in the air line of the brake system and connected to a weighted lever that is normally held in in- 20 active position by a latching mechanism, and an electroresponsive device connected with the lever and the latching mechanism in such manner as to relieve the lever of the influence of the latching mechanism and 25 move the lever initially upon the release of the latching mechanism, thereby permitting the lever to gravitate to active position to operate the valve to effect an application of the brakes. This electroresponsive device is 30 under the control of the road signals and is energized when the train runs by a signal set at danger.

With the above and other objects in view, the invention consists in the construction, 35 combination and arrangement of parts hereinafter set forth and falling within the scope of the claims.

In the accompanying drawings:

Figure 1 is a diagrammatic plan view of 40 apparatus constructed in accordance with the present invention.

Fig. 2 is a sectional detail of the valve casing and valve.

Referring now to the drawings in detail, 1 45 designates a trackway, while 2 indicates semaphores arranged along the trackway 1, and suitably spaced apart to divide the trackway into sections or blocks. Arranged adjacent to the entrance of each block are 50 contact rails 3 spaced apart in parallelism and connected to the opposite sides of a source of energy, as a battery 4, by means of wires 5. Located in one of the wires 5 is a circuit closer 6 connected by suitable mecha-

nism to the adjacent semaphore so that 55 when the semaphore blade moves to danger position the battery 4 will be connected in circuit with the contact rails. 3.

Connected in the air line of the brake system of the train, around the engineer's 60 brake valve, is a valve 7 arranged in a horizontal position. Connected with the stem of the valve 7 is a disk 8 and formed integral with the periphery of the disk 8 and projecting outwardly therefrom is a lever 9 65 normally disposed in a vertical position to hold the valve in normal position. On the upper end of the lever 9 is a weight 10 capable of adjustment along the lever and equipped with suitable means 11, whereby 70 the weight may be locked in adjusted position. Loosely mounted upon the stem of the valve 7 adjacent to the disk 8 is a trip lever 11' depending from the valve, and projecting outwardly from the disk 8 adjacent to 75 the opposite side edges of the trip lever are pins 12 disposed astride the trip lever to permit it to have a little lost motion. When it is swung in one direction far enough to engage these pins, the disk will be operated to overbear the lever 9 so that the weight 10 may swing the lever 9 and the disk to operate the valve 7 to a position to 80 effect the application of the brakes. Formed in the periphery of the disk 8 is a notch 13 85 and engaging the notch 13 is one end of a pawl 14 pivoted between its ends at 15 and normally held in latching position by means of a spring 16, the pawl 14, when in engagement with the notch 13, acting to prevent 90 accidental movement of the lever 9 incident to the jarring or vibration of the motor car. Fastened to the lever 11' adjacent to the lower extremity thereof is one end of a rod 17 projecting upwardly and outwardly 95 from the lever and having the outer end equipped with a stud 18 that engages the lower edge of the pawl 14 beyond the pivot pin 15. 19 designates an electromagnet whose armature is mounted on a lever 20 100 capable of swinging movement, and connected through the medium of a chain 21 to one end of a link 22, the other end of the link 22 being connected through the medium of a pin and slot connection 23 with the lower 105 end of the lever 11'. The terminals of the magnet 19 are connected, by means of wires 24, with brushes 25 of some suitable con-

struction carried by the motor car and adapted to wipe over the contact rails 3 in the travel of the car along the track.

In practice, when a signal blade is in danger position, and a train runs by such blade, the current from the battery 4 flows through the coil of the magnet 19 as soon as the brushes 25 engage the contact rails, thereby energizing the magnet 19. Upon the energization of the magnet 19 the armature lever 20 is moved, thereby pulling upon the chain 21 to swing the lever 11'. In this swinging of the lever the rod 17 operates the latching pawl 14 to disengage the notch 13, while the lever engages the pins 12 to initially move the disk and the lever 9. Succeeding this initial movement of the disk the weight 10 gravitates to lowered position, thereby operating the valve 7 to effect the application of the brakes.

I claim:—

1. In automatic train stopping apparatus, a valve connected in the air line and operable to secure an application of the brakes, a disk connected with the stem of said valve, pins in said disk, a lever connected to said disk and projecting normally upward to hold the valve in normal position, and a weight on the outer end of said lever adapted to swing the latter to operate the valve to brake applying position, combined with a second lever loosely mounted on the valve stem alongside said disk and capable of slight lost motion between said pins when moved on its pivot, and mechanism for swinging the second-named lever to start the movement of the disk and throw the first-named lever and its weight out of a strictly vertical position, for the purpose set forth.

2. In automatic train stopping apparatus, a valve connected in the air line and operable to secure an application of the brakes, a disk connected with the stem of said valve, a weighted lever connected to said disk and projecting normally upward to hold the valve in normal position said lever adapted to swing and move the valve to brake applying position, and means hold-

ing said disk in normal position, combined with a second lever movably mounted on the valve stem and pendant therefrom alongside the disk, a pin in the latter struck by this lever when moved out of its strictly vertical position, and tripping mechanism also carried by this lever for actuating said holding means and permitting the disk to turn under the influence of the weighted lever when the latter is thrown out of its strictly upright position.

3. In automatic train stopping mechanism, a valve connected in the air line and operable to secure an application of the brakes, a disk connected with the stem of said valve, a lever connected to said disk and projecting normally upward to hold the valve in normal position, a weight on the outer end of said lever adapted to swing the latter to operate the valve to brake applying position, a lever loosely mounted upon said valve stem and depending from the valve, means for operating this lever to initially move the first mentioned lever, and latching mechanism for said disk under the control of the second named lever.

4. In automatic train stopping mechanism, a valve connected in the air line and operable to secure an application of the brakes, a disk connected with the stem of said valve, a lever connected to said disk and projecting normally upward to hold the valve in normal position, a weight on the outer end of said lever adapted to swing the latter to operate the valve to brake applying position, a lever loosely mounted upon said valve stem and depending from the valve, means for operating this lever to initially move the first mentioned lever, said disk being formed with a notch, a pawl fulcrumed between its ends and having one end normally engaging said notch to hold the disk against movement, and a rod connected to said second named lever and adapted to actuate the pawl to release the disk upon the movement of the second named lever.

In testimony whereof I affix my signature.

FRANK ALBERT WALTON.
